UNITED STATES PATENT OFFICE.

GEORGE BARTLEY, OF CLEVELAND, OHIO.

MAIL-TAG.

SPECIFICATION forming part of Letters Patent No. 359,049, dated March 8, 1887.

Application filed December 15, 1886. Serial No. 221,655. (No model.)

To all whom it may concern:

Be it known that I, GEORGE BARTLEY, of Cleveland, in the county of Cuyahoga and State of Ohio, have invented certain new and useful 5 Improvements in Mail-Tags; and I do hereby declare the following to be a full, clear, and exact description of the invention, such as will enable others skilled in the art to which it pertains to make and use the same.

10 My invention relates to an improved tag or label designed more especially for the United States mail-service, which tag is bifurcated at one end to embrace the cord of a mail-sack and has hook-notches made in reverse order in 15 the respective prongs of the tag to receive the cord when the tag is given a quarter-turn, together with a spring-actuated push-bar to hold the cord in the notches, to the end that no extra cord is needed for securing the tag, that the 20 latter may be quickly attached to or detached from the cord of the mail sack, and when in position on the said cord is absolutely secure as against accidental displacement. The ordinary mail-sack has eyelets and a running cord 25 for securing the mouth of the sack. In ordinary practice a tag is secured to the mail-sack by means of an extra cord, the tag usually consisting of a block of wood with the destination and direction for return printed thereon. A 30 hole is made in one end of the tag and the latter is strung on a piece of heavy cord and is secured to the mail-sack by tying the tag-cord either around the sack or to the sack-cord, usually the latter. In removing the tag the tag- 35 cord is cut and thrown away, and when the tag is again wanted it is again strung, but on a new cord. The waste of cord thus accruing is in the aggregate enormous, as is also the waste of time in cutting such cord to lengths and 40 stringing the tags and tying the latter to the mail-sack.

As an improvement I have devised the tag illustrated in the accompanying drawings.

Figure 1 is a view in perspective showing 45 the upper portion of a mail-sack in its closed position with my improved tag in position thereon. Figs. 2 and 3 are plans, the former being partly in section and showing the cord in position in the notches, and the latter showing the push-bar depressed and the cord in 50 position to enter the notches.

A represents a portion of a mail-sack secured in the usual manner by the cord *a*, the latter being usually clamped or tied to hold the mouth of the sack closed. 55

B is the tag or "label," as it is sometimes called. The body of the tag is usually of wood, the destination of the sack and direction for the return of the same being usually printed on the wooden part. The tag has a metal head, 60 *C*, and the latter has wings or flanges *C'*, for embracing and attaching to the wood. The head is bifurcated to embrace the cord *a* of the sack, and has hook-notches *c* made in reverse position in the respective prongs of the head. 65 A notch commencing at the edge of the prong extends laterally and curves upward toward the end of the prong, and terminates midway of the prong in a lateral direction, as shown, so that the upper ends of the two notches are 70 in line with each other.

A push-bar, *D*, has a T-shaped head, *d*, that operates in the slot *c'* of the head. The shank of the push-bar extends into a chamber or socket, *b*, and is connected with a spiral spring, 75 *E*, the latter being secured at the bottom of the socket, as shown, by means of which arrangement the push-bar is thrust outward by the spring to the position shown in Fig. 2, but is held by the spring from being lost out of 80 the tag. In attaching the tag the prongs *c'* are placed astride the cord *a* and a slight pressure endwise of the tag is applied to depress the push-bar by forcing it against the cord. When the head of the push-bar has reached the bottom of the slot, as shown in Fig. 2, the cord is 85 in position to enter the notches, after which the tag is given a quarter-turn to force the cord into the notches. Meantime the end pressure on the tag is relieved and the spring-actuated 90 push-bar forces the cord to the upper end of the notches and holds it secure as against any possible displacement by accident. By reversing these movements of the tag the latter is detached from the cord, the attaching or detaching of the tag requiring but a moment's time. 95

In removing an ordinary tag by cutting the tag-cord some care must be exercised so as not to cut the sack or the sack-cord, the operation 100 requiring about the same time as the removal of my improved tag by an expert operator,

while my tag can be attached in much less time than the ordinary tag. In consideration of the cost of the tag cords, the time spent in cutting them to lengths and stringing the tags, it will be seen that the introduction of my improved tag will effect a great saving in mail service.

What I claim is—

1. A tag for attaching to the cord of mail sacks, the same having a bifurcated end for embracing the cord, hook-shaped notches made in reverse order in the respective prongs of the tags, and a spring-actuated device for holding the cord in the notches, substantially as set forth.
2. The combination, with the body of the

tag, of a metal bifurcated head for embracing the cord of the mail-sack, hook-shaped notches set in reverse order and made in the respective prongs of the head, and a spring-actuated bar, ²⁰ the head of which is made to operate between the prongs of the head of the tag to press the cord of the mail-sack to its seat in the notches, substantially as set forth.

In testimony whereof I sign this specification, in the presence of two witnesses, this 24th day of November, 1886.

GEORGE BARTLEY.
